MACHINE FOR GRINDING DRILL BITS

Fate Dixon, Durham, N. C., assignor of one-half
to Samuel A. Poole, Durham, N. C.

Application December 4, 1937, Serial No. 178,167

5 Claims. (Cl. 51—219)

My invention relates to a machine for sharpening or grinding the ends of drill bits or the like.

An important object of the invention is to provide a machine of the above mentioned character, having proper adjustments for grinding the angularly disposed faces upon the drill bit.

A further object of the invention is to provide a machine of the above mentioned character, the grinding action of which is manually controlled.

10 A further object of the invention is to provide a machine of the above mentioned character so constructed that the drill bit is manually rocked upon the grinding surface from the leading point to the trailing point.

15 A further object of the invention is to provide means for bodily raising and lowering the drill bit during the grinding action to properly distribute the wear upon the rotary grinding element or stone.

20 A further object of the invention is to provide a stop to engage with the drill bit when properly set in the chuck or holding jaws for grinding one face, and adapted to engage with the bit to properly locate the same in the chuck so that the other face will be ground at the same angle.

25 Other objects and advantages of the invention will be apparent during the course of the following description.

In the accompanying drawings forming a part 30 of this application and in which like numerals are employed to designate like parts throughout the same,

35 Figure 1 is a perspective view of a machine embodying my invention,

Figure 2 is a plan view of the same,

Figure 2a is an enlarged detailed view of the carriage movement indicating means,

Figure 3 is a side elevation of the same, showing the clamp holding the bit generally parallel 40 to the grinder and spaced therefrom,

Figure 3a is a detailed section taken on line 3a—3a of Figure 3,

Figure 3b is a detailed section taken on line 3b—3b of Figure 3,

45 Figure 4 is a side elevation of the machine, parts in section, with the bit clamp swung to a position to hold the bit in an angular position for contact with the rotary grinder,

Figure 4a is a detailed section taken on line 50 4a—4a of Figure 3,

Figure 5 is a plan view of the machine, showing the parts in the adjusted position as shown in Figure 3,

55 Figure 6 is a side elevation, parts in section,

with the bit clamp moved upwardly and inwardly with respect to the grinder,

Figure 7 is a side elevation of the bit clamp showing the gage rod,

Figure 7a is an enlarged end elevation of the 5 bit, associated elements being shown in elevation and broken away,

Figure 8 is a transverse section taken on line 8—8 of Figure 7,

Figure 9 is a plan view of the grinder, with 10 the bit contacting therewith and shown in section, and,

Figure 10 is a similar view, at right angles to Figure 9, illustrating the grinding action when the bit is swung upwardly.

15 In the drawings, wherein for the purpose of illustration is shown a preferred embodiment of my invention, the numeral 15 designates a horizontal bar which is bolted or otherwise rigidly attached to a horizontal support, such as a table 20 top. Rigidly attached to the horizontal bar 15 and projecting above the same are vertical arms 16, provided near their upper ends with bearings 17, rotatably receiving a horizontal shaft 18, driven by a pulley 19, engaged by a belt 20, 25 in turn driven by the rotary element of any suitable prime mover. Rigidly mounted upon the horizontal shaft 18 is a rotary grinding element or stone 21, clamped to the shaft 18 for rotation therewith, by any suitable means, and preferably 30 in a manner whereby the grinding element may be longitudinally adjusted upon the shaft 18.

A vertically swinging frame 22 is mounted upon the vertical arms 16, comprising side bars 23, the forward ends of which have openings 24 to pivotally receive a horizontal shaft 25, secured to the arms 16. The arms 23 are rigidly connected by horizontal rods 26, and these rods 26 are parallel with the rotary shaft 18.

35 Slidably mounted upon the guide shafts 26 of the frame 22 is a carriage 27, having openings 28, to receive the rods 26. This carriage is adapted to have rectilinear reciprocatory movement and is provided between the openings 28 with a screw-threaded opening 29, for receiving the 45 screw-threaded portion 30 of a rotary operating shaft 31. One reduced end 32 of the shaft 31 is rotatable within the opening 33, while the opposite end portion of the shaft is rotatable within an opening 34, and the shaft 31 has collars 35, 50 clamped thereon, upon opposite faces of the adjacent side 23. It is thus seen that the screw threaded shaft 31 can turn with respect to the sides 23 but cannot move longitudinally with relation thereto. The shaft 31 is turned by a 55

knurled head 35' or the like. It is thus seen that by turning the shaft 31, the carriage may be moved in a direction longitudinally of the shaft 18. The extent of movement of the carriage may be indicated by a scale 36 formed upon the sleeve 35, with a pointer 37 formed upon the adjacent arm 23. The scale 36 is preferably calibrated in one-thirty-second of an inch, starting from zero and extending in opposite directions. The scale 36 will indicate when the carriage 27 has been shifted longitudinally with respect to the grinding element 21 for one-thirty-second of an inch or any multiple thereof. Any other suitable form of calibration may be used, if desired.

15 The carriage 27 is provided near its rear end with a vertical cylindrical opening 38, to rotatably receive a sleeve 39, projecting above the carriage and having a disc 40 preferably formed integral therewith. This disc is provided with a 20 pointer 41 to coact with a scale 42, formed upon the rear end of the carriage 27, as shown. This scale is graduated in degrees for denoting the angular disposition of the edge of the cutting end of the bit, with respect to the end face of the rotary grinder. The end face of the bit is ordinarily beveled at about 45° with respect to its longitudinal axis and when this bevel is desired, pointer 41 registers with the degree designated "45" in the scale 42. To decrease the angle of bevel on 25 the bit, the disc 40 would be turned counterclockwise, while to increase the same the disc 40 would be turned clockwise. Means are provided to lock the sleeve 39 to the carriage 27 in the selected adjusted position, comprising a set 30 screw 43, having a knurled head 44 or the like. Rotatably mounted within the adjustable sleeve 39 is a vertical post 45, carrying a stop element 46, operating within a segmental slot 47, formed in the sleeve 39, to engage an end wall 48, to limit 35 the turning movement of the vertical post 45 in a counterclockwise direction, Figure 1, to bring the bevel face of the bit into contact with the end face of the rotary grinder. When the stop element 46 engages the end wall 48, the selected angle for 40 the edge 49 of the face of the bit is determined. This angle is ordinarily 45° with respect to the longitudinal axis of the bit although it may be increased or decreased.

Rigidly secured to the upper end of the post 45 is a head 50, having a horizontal opening 51, to pivotally receive a generally horizontal shaft 52, having a handle 53 rigidly secured thereto. Mounted upon the shaft 52 is a collar 54, adapted to be clamped to the shaft by a set screw 55 or the like. This collar carries a stop finger 56, operating above the head 50 and to contact with the top of the head when the shaft 52 is turned clockwise, Figure 5, to the limit of its clockwise movement. When the stop finger 56 engages the head 50, the bit preferably has its longitudinal axis disposed at about 45° from the vertical. This prevents any possibility of the rotary grinder swinging the bit downwardly during the grinding action. The angular position occupied by the bit 55 with respect to its longitudinal axis may be varied by turning the collar 54 upon the shaft 52 and again clamping the same to the shaft.

The work or bit holding device or chuck comprises a stationary jaw 57, rigidly secured to the 70 shaft 52 and this stationary jaw coacts with an opposed movable jaw 58, rigidly secured to a pair of rods 59, slidable within openings 60 formed in the jaw 57. The rods 59 are rigidly secured to a cross head 61, having a screw-threaded opening 75 62, for receiving a screw-threaded rod 63, turned

by a milled head 64. The inner end of this screw-threaded rod is arranged to contact with the stationary head 60 and thereby draw the movable jaw 58 toward the stationary jaw. The stationary jaw is provided with a V-shaped notch 65 5 to receive the side of the bit 66, to cause the same to be centered, as shown. It is thus seen that the jaws 57 and 58 will clamp the bit 66 between them and properly hold the bit during the grinding action. Rigidly attached to the stationary 10 jaw 57 is a guide rod 67, which is preferably square in cross-section and slidably receives thereon a carriage 68, which is clamped in adjustment at a selected longitudinal position upon the rod 67 by a set screw 69 or the like. The 15 carriage 68 has outwardly diverging jaws 70, affording a V-shaped recess 71, receiving the rear end of the bit 66. The guide rod 67 has a handle 72, as shown.

The stationary jaw 57 is provided upon its 20 forward face with a housing 73, rigidly secured thereto, having a V-shaped groove 74, to receive a gage rod 75. The gage rod is clamped in position by a set screw 76, turned by a handle 77. The gage rod is set to engage with the face 78 25 of the bit when the major portion of its edge 79 is vertical, when looking down upon the bit when in a generally horizontal position. After one face or bevel at the end of the bit has been ground, the bit is turned around in the work 30 clamp, by proper manipulation of the parts thereof and the gage rod 75 will then engage the face 80, so that the edge 81 of the bit will be vertically arranged. This renders it possible to quickly adjust the bit within the holder or clamp and render it certain that the two bevel faces will be ground at precisely the same angle.

The operation of the machine is as follows: The sleeve 39 may be adjusted to define the angle of bevel 49, Figure 9, and if this is to be 40 45° with respect to the longitudinal axis of the bit, the pointer 41 registers with "45" in the scale 42, and the sleeve 39 is clamped to the carriage in this selected adjusted position. The movable jaw 58 is now moved from the stationary jaw 57 45 so that the bit 66 may be inserted between the jaws, and the rear end of the bit will engage within the V-shaped notch 71. The rod 52 and the rod 67 are now raised, the stop finger 56 engaging the top of the head 51, and the vertical 50 post 45 is turned until stop pin 46 engages the end wall 48. In this adjusted position, the bevel end 49 of the bit should substantially contact the end face of the rotary grinder, but if it does not, the carriage 68 is moved forwardly from the 55 rod 67, until this occurs, after which the carriage 68 is clamped to the rod and the inner jaw 58 is moved toward the stationary jaw 57 to securely clamp the bit 66 between these jaws. Before the final clamping adjustment of the movable jaw 58, care is taken that the edge 79 of the bit is vertically disposed, which will position the bevel face 83 of the bit, next to the rotary grinder, in the proper position to contact with the end face of the grinder and be ground 60 thereby. The gage rod 75 is set to contact with the face 78, and is clamped in this position, so that it may readily engage the face 80, so that the edge 81 of the bit will be vertical when the bit is reversed, for grinding the bevel face 82. 70 With the parts thus adjusted, and the rotary grinder rotating toward the operator, the operator engages the handles 53 and 72 thereby raising the frame 22 and the elements carried thereby. The bevel face 83 of the bit is thereby 75

brought into contact with the end face of the grinder, and at the instant of contact the handle 72 is swung downwardly, while the handle 53 is moved upwardly and inwardly. Particular attention is called to the fact that the bit is held to one side of the shaft 53 and is therefore eccentric with respect to the shaft and the downwardly swinging movement of the handle 72 causes the face 83 to be ground into a slightly convex surface, Figure 10. The leading end of edge 49 is thus shifted from the end face of the grinder while the trailing end of this face is moved in contact with the grinding face. The inward movement of the bit with respect to the rotary grinding element distributes the wear upon the grinding element. When it is desired to increase the extent of grinding action, the bit is shifted bodily longitudinally toward the grinding wheel by advancing the carriage 27, by turning the operating shaft 31. It is thus seen that the bit holder is capable of swinging in a horizontal plane toward the rotary grinder and also in a vertical plane, and the work holder may be also bodily raised and lowered with respect to the rotary grinder by raising and lowering the swinging frame carrying the vertical post and the work holder may also partake of rectilinear reciprocatory movement by sliding the carriage supporting the post longitudinally of its rods. It is to be understood that the form of my invention herewith shown and described is to be taken as a preferred example of the same and that various changes in the shape, size and arrangement of parts may be resorted to without departing from the spirit of my invention or the scope of the subjoined claims.

Having thus described my invention, what I claim is:

1. In a machine for grinding the beveled end of a bit or the like, a substantially vertical rotary grinder, a relatively stationary support, a vertically swinging generally horizontal support arranged upon one side of and spaced from the rotary grinder and pivotally connected with the relatively stationary support to turn upon an axis extending longitudinally of the axis of rotation of the grinder, a carriage mounted upon the vertically swinging support, means to bodily move the carriage in a straight line with relation to the vertically swinging support in a direction longitudinally of the axis of rotation of the grinder, a generally vertical supporting device mounted upon the carriage and providing a turning axis arranged at generally a right angle to the plane of the carriage, a member mounted upon the generally vertical supporting device and permanently free to turn about the turning axis of the same within limits, a clamp disposed opposite the end of the rotary grinder and having means for holding a bit so that the longitudinal axis of the bit is arranged generally at a right angle to the end of the rotary grinder to present the end of a bit to the end of the grinder, and means to pivotally mount the clamping device upon the member so that the clamp is permanently free to be swung in a generally vertical plane while the edge of the bit engages the end of the grinder.

2. In a machine for grinding the beveled end of a bit or the like, a substantially vertical rotary grinder, a relatively stationary generally horizontal support, a vertically swinging support arranged upon one side of the grinder and pivotally connected with the relatively stationary support to turn upon an axis extending longitudinally

of the axis of rotation of the grinder, a carriage mounted upon the vertically swinging support, means to bodily move the carriage in a straight line with relation to the vertically swinging support in a direction longitudinally of the axis of rotation of the grinder, a sleeve pivotally mounted upon the carriage and having its turning axis arranged generally vertically at generally a right angle to the plane of the carriage, means to clamp the sleeve in the selected adjusted position against turning movement, a generally vertical post having limited turning movement in the sleeve, a clamp projecting to a position generally opposite the end of the rotary grinder and presenting the bit held therein to such end, a head carried by the post and having an opening arranged at substantially a right angle to the longitudinal axis of the post, and a shaft pivotally mounted within such opening and carrying the clamp so that the clamp may be swung in a generally vertical direction and a handle secured to the shaft to turn the same upon its longitudinal axis.

3. In a machine for grinding the beveled end of a bit or the like, a substantially vertical rotary grinder, a generally horizontal frame arranged beneath the grinder in spaced relation thereto, means to pivotally support the frame so that it may be swung vertically toward and from the periphery of the grinder, a carriage slidably mounted upon the generally horizontal frame to move in a straight line which is substantially parallel with the axis of rotation of the grinder, an operating shaft secured to the frame and having screw threaded engagement with the carriage to move the same in the said straight line, a generally vertical sleeve mounted to turn upon the carriage, the sleeve and carriage having means to indicate the extent of turning movement, means to clamp the sleeve to the carriage against turning movement, a generally vertical post permanently freely pivotally mounted within the sleeve for turning movements within limits, a block rigidly secured to the generally vertical post and having a generally horizontal opening, a generally horizontal shaft permanently freely pivotally mounted within the opening and having its forward end extending opposite the end of the grinder, a stop having a turning adjustment upon the shaft and a part to engage the block to limit the turning movement of the shaft, a handle secured to the shaft to turn the same upon its longitudinal axis, a clamp mounted upon that end of the shaft opposite the end of the grinder and having means to hold the bit so that the longitudinal axis of the bit will be arranged generally at a right angle to the shaft and the end of the grinder, and a handle secured to the clamp and projecting laterally outwardly from the same and disposed at generally a right angle to the first named handle.

4. In a machine for grinding the beveled end of a bit or the like, a substantially vertical rotary grinder, a relatively stationary support, a generally horizontal support arranged beneath and spaced from the rotary grinder, means to pivotally mount the generally horizontal support upon the stationary support so that it may be swung vertically toward and from the grinder, a guide device mounted upon the generally horizontal support and extending longitudinally thereof and projecting beyond one end of the rotary grinder, a carriage mounted upon the guide device, an adjusting screw to move the

- carriage longitudinally of the guide device, a generally vertical post mounted upon the carriage and having a turning axis, the post projecting upwardly beyond the carriage, a generally horizontal shaft arranged above the carriage and mounted upon the upper end of the post and turning about the axis of the post and adapted to turn upon its longitudinal axis, a clamp disposed opposite the end of the rotary grinder and mounted upon the generally horizontal shaft and having means to receive and hold the bit so that the longitudinal axis of the bit will be arranged generally at a right angle to the surface of the end of the rotary grinder, and means for raising the generally horizontal support and for turning the generally horizontal shaft to present the end of the bit to the end of the grinder at varying distances from the periphery of the grinder.
5. In a machine for grinding the beveled end of a bit or the like, a substantially vertical rotary grinder, a relatively stationary support, a generally horizontal support arranged beneath and spaced from the rotary grinder, means to pivotally mount the generally horizontal support upon the stationary support so that the generally horizontal support may be swung vertically to-

ward and from the grinder, a guide device mounted upon the generally horizontal support and extending longitudinally thereof and projecting beyond one end of the rotary grinder, a carriage mounted upon the guide device, an adjusting screw to move the carriage longitudinally of the guide device, a generally vertical post mounted upon the carriage and having a turning axis and projecting upwardly beyond the carriage, a head mounted upon the post to turn generally 10 horizontally about the turning axis of the post, said head having a generally horizontal opening, a rock shaft extending through the generally horizontal opening, an adjustable stop mounted upon the rock shaft and having a part 15 to engage with the head to limit the turning movement of the rock shaft, a handle mounted upon the outer end of the rock shaft, a clamp arranged opposite one end of the rotary grinder and mounted upon the rock shaft and having 20 means for receiving and holding the bit so that the longitudinal axis of the bit is arranged generally at a right angle to the face of the end of the grinder, and a handle connected with the clamp and disposed generally at a right angle 25 to the first named handle.

FATE DIXON.
